UNITED STATES PATENT OFFICE

JOHN A. RYMER, OF BERKELEY, CALIFORNIA, ASSIGNOR, BY MESNE ASSIGNMENTS, TO
RY-LOCK COMPANY, LTD., OF RENO, NEVADA, A CORPORATION OF NEVADA

DOORLOCK

Application filed June 30, 1928. Serial No. 289,401.

The invention relates to a lock of the latch bolt type having the bolt thereof normally arranged for withdrawal by means freely operable at both sides of the door.

5 An object of the invention is to provide an improved lock of the class described in which the bolt actuating means at one side of the door may be manipulated and disposed to prevent the operation of the bolt actuating means at the other side of the door.

10 Another object of the invention is to provide a lock of the class described in which key controlled means are provided in direct association with the operating means which is arranged to be rendered inoperative, whereby the bolt may be independently actuated by means of a key when said operating means have been rendered inoperative.

15 A further object of the invention is to provide a lock of the class described in which one structure may be mounted for use on doors of different thicknesses at either edge thereof and independently of their direction of swing.

20 25 A still further object of the invention is to provide a lock of the class described for indoor use in which an operation thereof by either of the means provided automatically restores the lock to its normal condition of free operation from either side.

30 Yet another object of the invention is to provide in a lock of the class described improved means for adjustably securing an operative spindle thereof to a knob constituting one of the primary operating means for the lock.

35 Still another object of the invention is to provide a lock of the class described having a particularly simple and efficient structure.

40 45 The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings,

Figure 1 is a fragmentary plan section taken through the lock and a door on which the lock is mounted.

Figure 2 is a view taken on the broken line 55 2-2 in Figure 1.

Figure 3 is a perspective view of a member shown in Figures 1 and 2.

Figure 4 is a sectional view taken on the line 4-4 in Figure 1.

Fig. 5 is a side sectional view of the latch-plate actuating mechanism, taken on a line corresponding to the line 5-5 of Fig. 4.

Figure 6 is a fragmentary section taken on the line 6-6 in Figure 5.

Figure 7 is an enlarged fragmentary view of the lock structure taken on the line 7-7 in Figure 1, a portion of the showing being in section.

Figure 8 is a sectional view at the line 8-8 70 in Figure 7.

Figure 9 is a view similar to Figure 7 but with the lock parts disclosed in a different operative relation.

The present embodiment of the invention 75 is incorporated in a lock 11 disposed in a suitable cavity 12 provided in the free edge portion 13 of a door 14, and which is arranged to be operated from the inner and outer sides of the door by means of knobs 15 80 and 16. The bolts 17 of the lock is arranged to normally extend from the outer end of a bolt casing 18 mounted in the door edge 13, such casing being laterally flanged adjacent the point of emergence of the bolt therefrom 85 whereby it may be mounted in fixed relation in and to the door edge, it being noted that the casing flange is also arranged to conceal the mouth of the portion of the cavity 12 which extends to the door edge.

90 95 Slidably mounted in the casing 18 is a bolt yoke or latch plate member 19 for actuating the bolt 17, such member being here shown hollow and of generally rectangular outline and being urged to assume and maintain an outer position by reason of a spring 21 operatively engaged behind it. The forward end of the latch plate 19 is perforated as at 22 for the sliding reception of a shank 23 extending inwardly from the bolt, such shank 100

being provided at its inner extremity with an enlarged head 24 which is arranged to limit the outward movement of the bolt shank through the opening 22. A compression spring 26 is disposed about the shank 23 and between the inner end of the bolt head and the outer end of the latch plate 19 whereby the bolt is arranged to be normally held extended from the latch plate for retraction therewith, and at the same time may be retracted independently of the latch plate. Journalled in the casing 18 to extend horizontally therethrough is a latch actuator 27 having extending therefrom intermediate the casing walls an arm 28 arranged for engagement with the latch plate 19 in such manner that a rotation of the actuator from the normal position shown in Figure 5 will effect a retractive displacement of the latch plate. Preferably, and as shown, the actuator arm 28 is arranged for engagement with the latch plate both at the upper and lower sides thereof whereby a rotation of the actuator in either possible direction may retract the latch plate.

The casing 18, it is noted, is formed with generally like and transversely separable sections 29 and 31, the plane of separation of the sections extending longitudinally of the 30 casing and perpendicular to the axis of rotation of the actuator 27. Ends 32 and 33 of the casing sections are extended for an overlapping relation, and flat flanges 37 and 38 at the other ends of the respective sections 35 are arranged to lie in coplanar relation whereby they may be simultaneously engaged in opposed grooves 39 provided at the back of an edge plate 41. The plate 41 is perforated to permit the protrusion of the 40 bolt therethrough, it being noted that the bolt must be pushed back beyond the plane of the plate 41 during the installation or removal of the plate. The plate 41 is also perforated above and below the bolt perforations to permit the use of screws 42 for securing it to the door edge. In this manner a 45 novel bolt casing is provided which may be assembled in a particularly simple manner.

Extending axially through the actuator 50 is a perforation 43 through which a spindle 44 is arranged to be engaged whereby the spindle may be used to effect an operative rotation of the actuator, it being noted that the spindle slidably engages the perforation 43. As shown, the perforation and spindle 55 are of like polygonal section for effecting an operative engagement thereof. The ends of the spindle 44 extend from both sides of the actuator, and are arranged to be connected 60 to the knobs 15 and 16 whereby they may be operated thereby. The spindle 44 is arranged to carry the knob 15 in fixed relation thereto at all times. As shown, the spindle end portion 46 arranged for engagement with 65 the knob 15 is threaded and has threadedly

and adjustably engaged thereon a member 47 providing a conically tapered friction face 48 for engagement in a complementary bearing recess 49 of the knob sleeve 51, the bore of the latter slidably and non-rotatably 70 engaging along the spindle portion 46, the sleeve bore and spindle portion both being of similar polygonal section. The free end of the spindle portion 46 is axially tapped and threaded to receive a screw 52 which engages through a knob perforation 53 with its head bearing against the knob at the outer end of its perforation 53. In this manner, with the member 47 set as required, the screw 52 may be tightened against the knob to 75 clamp the knob between its head and the member 47.

The knob 16, it will be noted, carries a key controlled tumbler barrel 54 axially journalled therein, the inner end of the barrel being provided with a recess into which the inner key end protrudes when the key is 80 fully engaged in the barrel, the latter relation being indicated in Figure 4. The sleeve portion 56 of the knob 16 is removably secured to the knob portion proper which carries the tumbler barrel, by means of screws 57 engaged through a radial flange at the outer end of the sleeve, said flange and the opposed knob surface preferably being provided with interlocking portions for preventing a relative rotation of the sleeve and knob independently of the screws 57.

Means are provided whereby the knob 16 and spindle 44 may be locked together against 90 relative rotation or released from such locked engagement by appropriate manipulations of the inner knob 15. As shown, the bore of the sleeve 56 is formed with three distinct 95 portions 58, 59 and 61 of differing diameters. The bore portion 58 is of circular section and has the smallest diameter of the three bore portions, the diameter thereof being, however, larger than the spindle portion engaged therethrough. Slidably mounted on 100 the spindle is a spool-shaped member 62 having one end flange 63 disposed inwardly of the inner end of the sleeve and the other end flange 64 engaging in the intermediate bore portion 59. A compression spring 65 is 105 mounted on the member 62 in encircling relation thereto, with one end of the spring engaging the flange 64 while the other end engages a shoulder 66 on the inner end of the sleeve 56. While slidable on the spindle, the 110 member 62 is arranged for rotation therewith, such being here shown effected by forming the bore of the member and the spindle portion engaged thereby of polygonal section. In this manner, the member 62 115 is arranged for rotation with the spindle at 120 all times.

Extending from the inner end of the sleeve 125 face 56 is a tapered projection 68, said projection being arranged for engagement in a 130

radial notch 69 provided in the opposed flange 63 of the member 62. The engagement of the projection 68 in the notch 69, it will be noted, locks the sleeve 56 to the member 62 for rotation therewith and with the spindle, it being further noted that the spring 65 is constantly operative to urge such engagement between the sleeve and member. Threadedly engaging the spindle outwardly of and against the member 62 is a nut 71, said nut being longitudinally slidably and non-rotatably engaged in the sleeve bore portion 59. Preferably, and as shown, the nut 71 is hexagonal and the bore portion engageable thereby is of like section whereby rotation of the nut in and with respect to the sleeve is prevented. It will now be clear that if the spindle be axially displaced to release the projection 68 from the notch 69 against the resistance of the spring 65, a relative rotation of the knob 16 and spindle 44 is permitted. And it will be further noted that the threaded engagement of the nut 71 with the spindle permits an adjustable mounting of the knob axially along the spindle.

Mounted on the spindle 44 outwardly of the nut 71 and in the outer bore portion 61 is a sleeve 72. The sleeve 72 slidably and non-rotatably engages the spindle, the spindle and sleeve bore being of polygonal section for this purpose, it now being noted that the entire spindle portion engageable within the knob sleeve is conveniently of the same section, since the member 62 is similarly engaged with the spindle at the inner end of said sleeve. The outer end of the sleeve 72 extends into the tubular barrel recess 55 and is diametrically slotted to receive the tip of a proper key 73. With the knob 16 relatively fixed, the insertion of the key releases the tumbler barrel for rotation in the knob and the spindle is turnable directly by the key, providing, of course, that the knob sleeve is not locked to the spindle by the member 62, which condition obtains when the spindle is disposed to free the projection 68 from the notch 69. In this manner, the spindle is arranged for a direct key operation thereof when the knob is inoperative with respect thereto. It is noted that the sleeve 72 is freely rotatable in the bore portion 61 and is held against axial displacement therein by reason of its engagement between the tumbler barrel and the shoulder 74 defining the inner end of said bore portion.

Means are provided for holding the outer knob 16 in fixed relation to the door and the bolt casing 18, said means being hereinafter described. With the knob and its sleeve 56 thus held against movement, the spindle 44 must be moved axially inwardly of the door to disengage the notch 69 of the flange 63 from the knob projection 68, and such movement is arranged to be effected by an inward pull on the inner door knob 15. Since such

inward disposal of the spindle renders the outer knob inoperative to rotate the spindle for withdrawing the latch bolt and at the same time permits the use of a key for opening the door from the outside thereof where- 70 by the lock then constitutes a key lock, means are provided whereby the spindle may be held set in said position against the resistance of the spring 65. Accordingly, and as shown, a plate 75 is mounted on the spindle 44 between the bolt casing 18 and the outer knob sleeve 56, said plate being swivelled on the spindle for axial displacement therewith. In the present embodiment, the plate 75 is provided with a radial notch 76 extending 75 from its center and having the plate edge portions at its inner end engageable in an annular groove 77 provided in the spindle. Extending axially from opposite sides of the plate 75 toward the knob sleeve 56 are extensions 78, said extensions being arranged for sliding engagement in a pair of cooperating slots 79 provided in the cylindrical surface of the sleeve. When the plate extensions 78 are engaged in the slots 79, the plate 75 is arranged to be held against lateral removal from its swivelled engagement with the spindle, it being also noted that such engagement of the extensions in the slots locks the plate against relative rotation with respect to the sleeve. The extensions 78 are of such length that they maintain their engagement in the slots both when the spindle is moved inwardly to effect a release of the knob 16 therefrom and for different adjusted distances between 80 the knob sleeve and the bolt casing. 90

Extending laterally from latch plate 19 through slots 81 provided in the bolt casing 18 and toward the plate 75 is an extension 82, 95 said extension being provided with an opening 83 adjacent its outer extremity for the reception of a radial extension or detent 84 provided on the plate 75. The free edge of the latch plate extension 82 is bevelled and this extension is so related to the plate extension 84 that when the latter is moved inwardly, it forces back the former against the resistance of the latch plate spring 21 until the detent 84 enters the opening 83. In this manner a simple detent means is provided 100 for holding the spindle in its inner position. It is noted that when the detent 82 is engaged in the opening 83, a rotation of the plate 75, and so of the knob 16, is prevented, thereby 110 both holding the knob fixed during the actuation of the key therein and indicating that the door is locked. Preferably and as shown, pairs of oppositely related extensions 82 and 84 are provided on the latch plate 19 and 115 plate 75 respectively whereby the positions of the knobs may be reversed with respect to the bolt casing. It is noted that the relation of the parts when the spindle is set in its inner position is shown in Figure 9, while 120 125 130

Figures 1, 4, 5 and 7 disclose the lock parts as related when the outer knob 16 is operable for actuating the spindle.

Release of the spindle to return to its outer position is effected whenever the spindle is rotated to displace the latch plate for disengaging the extension opening 83 from the detent 84. In this manner, a rotation of the spindle from either side of the door restores the spindle to its outer position and renders the lock operable by means of the outside knob, it being clear that the lock is always operable by means of the inner knob. This feature as to the disposal of the spindle is particularly valuable when the lock is used on inside doors, since the lock must be deliberately set for key operation following each opening actuation thereof.

An escutcheon plate 85 for engagement against the outer door surface is mounted on the sleeve 56 of the outer knob 16. As shown, the plate 85 is of circular outline and is provided with a circular opening 86 for the reception of the sleeve 56. The sleeve 56, it is noted, is provided with an annular groove 87 adjacent its inner end, said groove extending substantially to the bottom of the slots 79. Projections 88 extend inwardly from the edge of the escutcheon opening 86 for engagement in the groove 87, said projections being placed in said groove by advancing them through the slots 79 as far as the groove and then rotating the escutcheon plate to a greater or less degree about the sleeve. The escutcheon plate, it is noted, extends outwardly along the sleeve and cooperates with the knob to hold an annular shell 89 in place, said shell completing the concealment of the sleeve.

Extending axially inwardly from the escutcheon plate 85, is a cylindrical shell 91, said shell being cut away at opposite sides to receive the bolt casing 18 transversely therethrough, preferably in fitted relation. Segmental webs 92 are provided across the inner ends of the portions of the shell 91, said webs being provided with threaded perforations 93. A plate 94 is provided for disposal against the inner door side, said plate being perforated for the free reception of the spindle 44 therethrough. Screws 95 extend through the plate 94 for engagement in the perforations 93 of the webs 92 whereby the door is arranged to be clamped between said plate and the escutcheon plate 85. The nut 47, it is noted, is preferably arranged to be disposed closely adjacent the plate 94 when the spindle is in its outer position, and as here shown said nut is provided with an extension for fitted engagement in the plate perforation at the spindle whereby the plate may be properly set before the screws 95 are tightened.

It will now be clear that with the lock of my invention installed on a door and having

the knob spindle in its outer position, a person may actuate the lock for opening the door by means of either knob. If, however, the person wishes to prevent the opening of the door from the outside, it is merely necessary to pull the inner knob 15 inwardly and away from the door to a position to release the outer knob 16 from the spindle 44 and to engage the detent 84 of the plate 75 in the opening 83 of the latch plate extension 82. The use of a key in the tumbler barrel 54 is then required for opening the door from the outside. By and upon the use of a key, or the opening of the door by means of the inner knob, the spindle and inner knob are freed to assume their outer position whereby the outer knob is automatically restored to its operativeness. The adjustable mounting of the knobs on the spindle and the reversibility of the operative parts for alternately connecting the outer knob with the latch plate and spindle makes possible the use of a single model of the lock on doors of different thickness and doors hung in various relations to their openings, whereby the lock is arranged for universal application without alteration.

I claim:

1. In a lock, a latch bolt and a spindle whereby it is directly actuated, a rotatable knob carried by the spindle and normally releasably engaging with the spindle for rotating the same, means carried by said knob for operating said spindle with a key, and means operative upon an axial displacement of the spindle with respect to the knob to release the knob from operative engagement with the spindle and lock the same against rotation.

2. In a lock, a latch bolt, a movable latch plate for said bolt, a spindle whereby the latch plate is directly actuated, an operating member for said spindle releasably engaged therewith, and means operative by and upon an appropriate manipulation of the spindle to release the member from its operative engagement with the spindle and to lock it to the latch plate for preventing an operative movement of the member.

3. In a lock, a latch bolt, a movable latch plate for said bolt, an axially displaceable spindle whereby the latch plate is actuated, an operating member for said spindle releasably engaged therewith, and means operative by and upon an axial displacement of the spindle to release the member from its operative engagement with the spindle and to lock it to the latch plate for preventing an operative movement of the member.

4. In a lock, a latch bolt, a movable latch plate for said bolt, an axially displaceable spindle whereby the latch plate is actuated, an operating member for said spindle releasably engaged therewith and rotatable about the axis thereof, means operative by and upon an axial displacement of the spindle to re-

lease the member from its operative engagement with the spindle, and means operative between the member and latch plate when said release of the member is effected for securing the member against rotation.

5. In a lock, a latch bolt, a reciprocable latch plate for said bolt, an axially displaceable spindle whereby the latch plate is actuated, an operating member for said spindle 10 releasably engaged therewith and rotatable about the axis thereof, means operative by and upon an axial displacement of the spindle, to release the member from its operative engagement with the spindle, a member 15 swivelled to said spindle and engaged with said first member for rotation therewith, and cooperative means on said latch plate and said second member engageable to secure said first member against rotation when said spindle is in an axially displaced position.

6. In a lock, a latch bolt, a reciprocable latch plate for said bolt, an axially displaceable spindle whereby the latch plate is directly actuated, an operating member for said 25 spindle releasably engaged therewith, means operative by and upon an axial displacement of the spindle to release the member from its operative engagement with the spindle, means yieldingly resisting said displacement 30 of the spindle, and cooperating means on said spindle and latch plate for releasably retaining the spindle in its displaced position.

7. In a lock, a latch bolt, a reciprocable latch plate for said bolt, an axially displaceable spindle whereby the latch plate is actuated, an operating member for said spindle 35 releasably engaged therewith, means operative by and upon an axial displacement of the spindle to release the member from its operative engagement with the spindle, means yieldingly resisting said displacement of the spindle, and cooperating means on said spindle and latch plate for releasably retaining 40 the spindle in its displaced position, said last means being arranged to be released by and upon an operative displacement of the latch plate.

8. In a lock, a latch bolt, a reciprocable 50 latch plate for said bolt, an axially displaceable spindle whereby the latch plate is actuated, an operating member for said spindle releasably engaged therewith and rotatable 55 about the axis thereof, means operative by and upon an axial displacement of the spindle to release the member from its operative engagement with the spindle, means cooperative between the spindle and member to 60 silently resist said displacement of the spindle, a member swivelled to said spindle and engaged with said first member for rotation therewith, and cooperative means on said latch plate and said last member engageable 65 to retain the spindle in its displaced position

and to secure said last member against rotation.

In testimony whereof, I have hereunto set my hand at Oakland, California, this 18th day of June, 1928.
